No. 36,915.

Patented May 17, 1904.

UNITED STATES PATENT OFFICE.

GUSTAVE F. KOLB, OF MOUNT VERNON, NEW YORK.

DESIGN FOR A CUP.

SPECIFICATION forming part of Design No. 36,915, dated May 17, 1904.

Application filed April 19, 1904. Serial No. 203,949. Term of patent 3½ years.

To all whom it may concern:

Be it known that I, GUSTAVE F. KOLB, a citizen of the United States, residing at Mount Vernon, county of Westchester, and State of New York, have invented a new, original, and ornamental Design for Cups, reference being had to the accompanying drawing, which is a perspective view of a cup, showing my new design.

What I claim is—

The ornamental design for a cup, substantially as herein shown.

GUSTAVE F. KOLB.
